UNITED STATES PATENT OFFICE.

GEORGE H. GROVE, OF HARRISBURG, PENNSYLVANIA.

AUTOMATIC SELF-CLOSING FUNNEL.

1,343,867.

Specification of Letters Patent. Patented June 15, 1920.

Application filed July 14, 1919. Serial No. 310,560.

To all whom it may concern:

Be it known that I, GEORGE H. GROVE, a citizen of the United States, residing at Harrisburg, in the county of Dauphin and State of Pennsylvania, have invented certain new and useful Improvements in Automatic Self-Closing Funnels; and I do declare the following to be a full, clear, and exact description of the invention, such as will enable others skilled in the art to which it appertains to make and use the same.

This invention relates to certain new and useful improvements in automatic self-closing funnels.

The primary object of the invention is to provide a funnel with a valve which will automatically close to shut off the liquid passing through the funnel when the liquid in the container which is being filled has reached a predetermined height, thereby preventing said container from becoming filled too full and spilling some of the liquid.

Another object of the invention is to provide a funnel with capacity graduations so that the liquid may be measured after it has been poured into the funnel.

A further object of the invention is to improve upon devices of this nature by the provision of an extremely simple, strong, durable and inexpensive construction, which will be efficient and reliable in operation, and well adapted to the purpose for which it is designed.

With these and other objects in view, the invention consists of certain novel features of construction, and the combination and arrangement of parts as will be hereinafter fully described and claimed.

In the accompanying drawings forming part of the application and in which similar reference characters designate like parts throughout the several views:—

Figure 1 is a vertical sectional view through a funnel constructed in accordance with this invention;

Fig. 2 is a similar view taken substantially on the plane indicated by the line 2—2 of Fig. 1; and,

Figs. 3 and 4 are transverse sectional views taken on the planes indicated by the lines 3—3 and 4—4 of Fig. 1.

The improved funnel consists of an inverted cone-shaped body 1 having its upper edge flared over or beaded to reinforce it, and being provided with a tubu-

lar threaded portion 2 at its lower end. Threaded to the portion 2 is a spout consisting of an upper section 3 and a lower section 4, said sections being tubular in shape, 60 being spaced a short distance apart, and being connected by two or more comparatively narrow straps 5. The upper end of the lower section 4 is provided with a cone-shaped wall 6 having a centrally disposed opening 7 therein for a purpose to be hereinafter described. The upper section 3 has disposed therein a screen 8 which acts as a strainer when liquid is passing through the funnel.

Extending transversely across the body 1 at the lower end thereof is a partition 9, the latter being soldered or otherwise secured to the walls of the body and being provided with apertures 10 which are preferably three 75 in number arranged in alinement with one another. Extending transversely across the body 1 at the upper end thereof and secured to the wall of the same by screws or rivets 11 is a bar 12. Connected to this bar 12 is 80 a hollow housing 13, of triangular configuration and having a cylindrical portion 14 at its lower end which extends through the central opening 10 in the plate 9 and is flared so as to completely close this opening. 85 The bar 12 and the plate 9 therefore form a means for rigidly supporting the housing 13. Carried by the housing 13 and extending transversely of the body 1 is a plate 15. This plate 15 is disposed a short distance 90 above the partition 9 and is provided with openings 16 arranged directly above the other two openings 10 of the plate 9.

Fulcrumed between its ends in the upper portion of the housing 13 is a lever 17, one 95 arm or end of which is connected by a rod 18 to a valve 19. This valve 19 is in the form of a plate which fits tightly against the partition 9 over the two end holes 10. This plate is provided with a central opening 20 to provide for the reception of the cylindrical portion 14 of the housing 13. Extending upwardly from the valve plate 19 and projecting through the apertures 16 in the plate 15 are stems 21 which serve to 100 guide the valve plate. The other end or arm of the lever 17 is connected to a rod 22 which extends through the bottom of the body 1 and entirely through both sections of the spout, said rod extending 105 through the aperture 7 aforementioned whereby it is guided. The lower end of the

rod 22 is threaded to provide adjustable mounting for a float 23 which it carries. The float is disposed in the lower section 4 of the spout and has a vertical movement in the same.

5 The bar 12 is provided with an opening 24, and through this opening projects a handle 25 carried by the lever 17. By means of this handle 25 the lever may be rocked 10 from one position to another to close or open the valve 19. On one side of the housing 13 is disposed a series of graduations 26. By these graduations 26 the amount of liquid disposed in the funnel may be determined.

15 The parts are normally in the position shown in Fig. 1 of the drawings, the weight of the float 23 overbalancing the weight of the valve 19 so as to hold the latter in opened position. When the funnel is being used and liquid is being poured into the same the valve 19 will remain in its uppermost position to allow the liquid to pass through the openings 10 in the plate 9 and into the upper section 3 of the spout. When 20 the liquid in the receptacle which is being filled rises into engagement with the float 23, the latter will consequently rise and through the medium of the rod 22 will rock the lever 17 so as to close the valve 19 and 25 cut off the flow of the liquid. Hence the receptacle will not be filled above a predetermined height. In view of the fact that the float 23 is adjustable upon the rod 22 the automatic closing of the valve may be regulated so that the receptacle may be filled to different heights.

If it is desired to measure a quantity of liquid before allowing the same to pass through the funnel, it is only necessary to 40 engage the operating handle 25 and shift the lever 17 so as to close the valve 19. The quantity of liquid poured into the body of the funnel can then be read from the series of graduations 26.

45 From the foregoing description taken in connection with the accompanying drawings, the construction, use and operation of the invention will be readily understood.

Various changes in form, proportion, and 50 in the minor details of construction may be resorted to without departing from the spirit of the invention as defined in the claims.

What is claimed is:

1. A funnel comprising an inverted cone-shaped body, a spout carried at the lower 55 end of said body, a partition extending transversely across said body at the lower

end thereof and being provided with a valve seat, a bar extending transversely across said body at the upper end thereof, a housing 60 supported within said body upon said partition and said bar, a valve disposed upon said seat, a float disposed in said spout, a lever fulcrumed within said housing, and rods connecting said float and said valve 65 with said lever whereby said valve is closed when said float is occupying its uppermost position.

2. A funnel comprising a body and a spout, said body having a valve seat therein, 70 a housing supported in said body and having an opening in the upper side thereof, a valve disposed upon said seat, a float disposed in said spout, a lever fulcrumed intermediate of its ends within said housing, 75 rods connecting the opposite ends of said lever with said valve and said float respectively to close said valve when said float is in its uppermost position, and a handle formed integrally with said lever and projecting laterally from the intermediate portion thereof through the opening in said housing, whereby said valve may be manually operated.

3. A funnel comprising an inverted cone-shaped body, a spout carried at the lower end of said body, a partition supported within said body and extending transversely across the lower end thereof, said partition being provided with a pair of openings 85 therein disposed on opposite sides of the center portion thereof, a housing supported within said body, a plate supported by said housing and spaced a slight distance above said partition, said plate having apertures 90 therein aligned with the openings of said partition, a valve plate disposed beneath said plate and movable toward and away from said partition and positioned so as to close the openings therein, guide pins projecting upwardly from said valve plate and extending through the apertures in the first mentioned plate, a float movably mounted in said spout, a lever fulcrumed in said housing, and rods connecting said float and said valve plate with said lever whereby said valve is closed when said float is occupying its uppermost position.

In testimony whereof I have hereunto set my hand.

GEORGE H. GROVE.
